LOCOMOTIVE BOILER

Bert E. Larson, Park Ridge, and Gust J. Christensen, Chicago, Ill., assignors to Locomotive Firebox Company, Chicago, Ill., a corporation of Delaware

Application May 20, 1940, Serial No. 336,161

8 Claims. (Cl. 122—68)

This invention relates to improvements in locomotive boilers and it consists of the matters hereinafter described and more particularly pointed out in the appended claims. The invention is more especially concerned with locomotive boilers having a firebox in which is located one or more water steaming and circulating elements that cause a flow of water from the lower portion of the boiler, forward of the main firechamber of the firebox, to a higher part of the boiler water space rearward of the flue sheet of the firebox.

One example of a water steaming and circulating element is a siphon of the so-called duplex type. Duplex siphons include a hollow body having a plurality of inlet necks or intakes.

In the use of a siphon of this type, the body has a top end outlet that usually opens through the crown sheet to discharge steam and water into the boiler space above the crown sheet to keep the same flooded even under low water conditions. The plurality of inlets for said body open through certain other sheets of the firebox to take in water from a lower portion of the boiler. Duplex siphons of this kind are especially advantageous for use in connection with the relatively long fireboxes and which may include a combustion chamber in conjunction with the main firechamber.

One of the objects of the present invention is to provide a locomotive boiler having a duplex siphon equipped firebox of the combustion chamber type, which is so constructed that a better water circulation is established throughout the length of the boiler and whereby the temperature of the water is more fully and quickly equalized, thereby reducing cracks and checks in the sheets of the firebox, as well as avoiding leaking stay bolts and other conditions which make frequent servicings necessary and increase maintenance expense.

Another object of the invention is to provide a locomotive boiler having one or more duplex siphons in the firebox thereof that function to take in water not only from toward the front end of the boiler water space but also from parts of said water space adjacent the front of the firebox and thereby establish a more rapid circulation of water from said parts to eliminate any quiet areas in the front throat and side water legs and thus avoid the deposit of solids in the bottom of said throat and side water legs.

Also, it is an object of the invention to provide a locomotive boiler having duplex siphons in its firebox and wherein the intakes of said siphons

in no way interfere with or disturb the setting of the brick making up the fire arch of the firebox when such an arch is desired.

The above mentioned objects of the invention, as well as others, together with the advantages thereof, will more fully appear as the specification proceeds.

In the drawings:

Fig. 1 is a longitudinal vertical sectional view through a locomotive boiler embodying one form of the invention.

Fig. 2 is a transverse vertical sectional view, on an enlarged scale, through a part of the firebox end of the boiler as taken on the line 2—2 of Fig. 1.

Fig. 3 is a transverse vertical sectional view through a part of the boiler forward of the firebox as taken on the line 3—3 of Fig. 1.

Fig. 4 is a longitudinal, horizontal fragmentary sectional view, on a scale enlarged over Fig. 1 and as taken on the line 4—4 of said Fig. 1.

Fig. 5 is a longitudinal vertical sectional view through the firebox end of a locomotive boiler embodying a modified form of the invention.

Fig. 6 is a transverse vertical sectional view through the firebox end of the boiler construction shown in Fig. 5 as taken on the line 6—6 of said Fig. 5.

Referring now in detail to that embodiment of the invention, illustrated in Figs. 1 to 4 inclusive of the accompanying drawings, the improved boiler comprises a relatively long barrel or shell 10 at the front end of which is a smokebox 11 and in the rear end of which is a firebox indicated as a whole at 12. The smokebox which is separated from the steam and water space 13 of the barrel by a flue sheet 14, is closed at its front end 11a and at the top of the smokebox is mounted a stack 11b.

The firebox 12 is herein shown as being of the combustion chamber type to include a main fire chamber 12a and combustion chamber 12b, the front end of which is defined by a flue or tube sheet 14a. The firebox includes side sheets 15, a crown sheet 16, a back sheet 17 and a front throat sheet 18. The crown sheet and a part of the side sheets extend forwardly of the throat sheet to form the top and the sides of the combustion chamber 12b and the bottom 19 of the combustion chamber merges at its rear end into the top end of the throat sheet 18. Tubes or flues 20 are operatively connected at their ends in the flue sheets 14—14a respectively, for the passage of products of combustion from the fire-

box 12, as a whole, to the smokebox 11 for discharge up the stack in the usual manner.

The rear end of the boiler shell includes outer side sheets 21, an outside back sheet 22 and an outside front throat sheet 23. The sheets 21, 22 and 23 coact with certain sheets of the firebox to define the side water leg 24, the back water leg 25 and the front throat 26, all bottomed by a mud ring 27. The front end of the side water legs and the top portion of the throat 26 are in open communication with the steam and water space 13 of the boiler forward of the main firechamber 12a of the firebox.

Of course, the various boiler and firebox sheets above mentioned are staybolted in the conventional manner (but not herein shown) and portions of the inside and outside back sheets 17 and 22 are mutually formed to provide a fuel door opening 28. The feed water enters the boiler through a so-called check valve 29 which in this instance is shown in Fig. 1 as being located on the top longitudinal center line of sheet near the flue 14, the barrel or shell 10.

The firebox is herein illustrated as containing one or more water steaming and circulating elements, each indicated as a whole at 30. In the present instance, said elements are constituted by the syphons of the so-called duplex type. When only one syphon is employed, say in a relatively narrow firebox, it is disposed in the longitudinal median line thereof. When two of such syphons are employed in a wider firebox, then one syphon is disposed upon each side of said median line, as appears in Fig. 2. If more than two syphons are used, they are substantially equally spaced.

Each syphon as here shown, includes a flat, hollow body formed to provide front and rear end compartments 31—32 separated by an intermediate shallower compartment 33. Each body includes vertically spaced side walls 34—34 and front and rear end walls 35 and 36 respectively. The side walls and the front and rear end walls are flared outwardly around the entire top end of the body to provide a marginal flange 37 that is fitted and welded into a suitable longitudinal opening in the crown sheet 16. Thus the open top end of the body provides a common discharge for all three compartments of the syphon body, into the steam and water space 13 of the boiler, above the crown sheet.

Associated with the rear compartment of the body of each syphon is a downwardly and forwardly extending tubular inlet neck 38 of substantial length and the front end thereof fits in and is welded to a flexible diaphragm 18a in the inside throat sheet 18. Associated with the bottom end of the front compartment is a downwardly and forwardly inclined tubular inlet neck 39 disposed at a lesser angle than the inlet neck 38 so as to be directed toward the front end portion of the bottom part of the combustion chamber 12b to terminate in a relatively short curved part 39a.

The bottom of the intermediate compartment 33 is formed by a part 40 of a substantially circular formation and which at one end joins a part of the inlet tube 38 and which at the other end merges into that part of the syphon body that bottoms the front end compartment 31 thereof. With the arrangement of the necks 38 and 39 as described and shown in Fig. 1, the neck 39 is spaced above the inlet neck 38.

Associated with the inlet neck 39 of each

syphon is an intake tube 41 which is preferably of the same diameter as said neck 39. Each intake tube 41, which is relatively long, is butt welded to the curved part 39a of the associated neck 39. Each intake tube 41 passes through an opening in the flue sheet 14a provided therefor by the removal or omission of certain of the tubes or flues 20 at the bottom of the group of the same. Each intake tube is welded to the flue sheet 14a from inside the firebox where it passes through said sheet.

The front end of each intake tube extends to a point relatively near the front flue sheet 14. As a considerable portion of each intake tube is disposed forwardly of the flue sheet 14a and in a position above the bottom of the shell 10 so as to be completely surrounded by the water therein, it is suitably supported in its operative position. One convenient way to support this part of each tube is by means of a plurality of longitudinally spaced chairs 42 or stands resting upon and rising from the bottom of the barrel or shell. The forward extremity of said intake tube is wide open. In the flue sheet 14 axially in line with said extremity is a washout plug 43.

It is pointed out that when the improved construction is being embodied in a new boiler, openings for certain flues 20 are omitted from the flue sheet 14a to provide areas required for the openings in said flue sheet for the passage of the intake tubes 41 therethrough. When the improved structure is being embodied in a boiler already in service, certain of the flues 20 are removed and openings left thereby in the flue sheets 14 and 14a are plugged. This provides the closed areas in the flue sheet 14a through which other openings are formed for the passage of the intake tubes therethrough. In this respect, it is pointed out that the flues 20 removed for this purpose are those disposed adjacent the bottom of the barrel. This, however, does not substantially reduce the efficiency of the boiler because said flues are often filled with cinders to such an extent that they have but little evaporative value. If a fire arch is desired, parts of the brick 44 therefor are engaged in supporting relation upon the intake tubes 38 as appears in Fig. 1.

In Fig. 5, we have illustrated a modified form of boiler construction and wherein certain of the parts which are the same as in Figs. 1 to 4 inclusive, bear the same reference numerals. In the construction shown in said Fig. 5 the inlet neck 38x for the rear compartment of the body is disposed at such an angle as to be directed toward the bottom portion of the flue sheet 14a. Adjacent the flue sheet, said neck has connected to it, the associated end of an intake tube 41, the same as embodied in the structure of said Figs. 1 to 4 inclusive. The intake neck 39x associated with the front compartment 31 of the syphon body is shorter than the intake neck 38x and the end of said neck is formed as a laterally and outwardly extending elbow or bend 39y which opens through the upper portion of a side sheet of the firebox.

In the operation of the construction shown in Figs. 1 to 4 inclusive, water is taken into the intake tubes 41 from the front end portion of the water space 13 of the boiler and enters the inlet neck 39 which leads to the front end chamber 31 of the associated syphon. Also, water is taken into the intake tube 38 from the throat 26 and enters the rear end chamber 32 of the syphon. The two streams of water entering the syphon

from the inlets 38 and 39 commingle in the siphon body, thereafter to pass upwardly into the steam and water space 13 with a gushing action above the crown sheet which is always kept flooded even under low water conditions. By the arrangement described, much longer portions of the siphons are disposed in the firebox than heretofore has been possible and therefore, the effective evaporating surface is materially increased. Also, the longer inlet made possible by the arrangement described gives a greater flexibility so that the parts of the siphon may move relatively under temperature chambers without cracking or other damage.

With respect to the structure shown in Figs. 5 and 6, a part of the water is drawn into the rear end chamber 32 of the body of each siphon from the front end portion of the water space 13 of the boiler while a part of the water is drawn into the front chamber 31 of the body of each siphon from the adjacent side water leg.

In either instance, a better water circulation is established throughout the boiler to eliminate any quiescent areas therein so that it remains in a cleaner condition for a longer period of time and at the same time a greater and more effective evaporating surface is afforded for the boiler, thereby increasing its efficiency.

While in describing the invention, we have referred in detail to the form, arrangement and construction of the parts involved, the same is to be considered only in the illustrative form so that we do not wish to be limited thereto except as may be specifically set forth in the appended claims.

We claim as our invention:

1. In combination with a locomotive boiler embodying therein a shell having a firebox at its rear end and a steam and water space above as well as forwardly of said firebox and which firebox includes a crown sheet and a flue sheet, water steaming and circulating means in the firebox and having a plurality of inlet portions, one of said inlet portions extending through and forwardly of the flue sheet into and longitudinally of said steam and water space in a plane above the bottom thereof and entirely surrounded by the water in said space and adapted to take in water from the forward portion thereof, and another of said inlet portions opening through another sheet of the firebox other than and at a point below the crown sheet, said water steaming and circulating means having an outlet opening through one of the sheets of the firebox.

2. In combination with a locomotive boiler embodying therein a shell having a firebox at its rear end and a steam and water space above as well as forwardly of said firebox and which firebox includes a crown sheet and a flue sheet, water steaming and circulating means in the firebox having an outlet opening through the crown sheet and a plurality of inlet portions, one of said inlet portions extending through and forwardly of the flue sheet into and longitudinally of said steam and water space in a plane above the bottom thereof and entirely surrounded by the water in said space and adapted to take in water from the forward portion thereof, and another of said inlet portions opening through another sheet of the firebox other than and at a point below the crown sheet.

3. In combination with a locomotive boiler embodying therein a shell having a firebox at its rear end and a steam and water space above as well as forwardly of said firebox and which fire-

box includes a crown sheet and a flue sheet, a water steaming and circulating element disposed in a substantially upright position and extending longitudinally of the firebox and including a flat hollow body, means providing an outlet for said body opening through the crown sheet into that part of said steam and water space above the same, means providing a plurality of inlet portions for said body, one for the front portion of the body and one for a portion of the body rearwardly of said front portion, one of said inlet portions extending longitudinally of but above the bottom of the shell and being arranged to take in water from a point in advance of the flue sheet toward the front end of said steam and water space and the other of said inlet portions opening through another of the sheets of the firebox other than and at a point below the crown sheet.

4. In combination with a locomotive boiler embodying therein a shell having a firebox at its rear end and a steam and water space above as well as forwardly of said firebox and which firebox includes a crown sheet and a flue sheet, a water steaming and circulating element in the firebox and including a flat hollow body arranged longitudinally in the firebox in a substantially upright position and having a part opening through the crown sheet for the outlet of water from said body into said steam and water space, means providing a plurality of inlet portions for said body, one for the front end of said body and one for the rear end of said body, the inlet portion for the front end of the body opening through and extending forwardly from the flue sheet and longitudinally of the shell toward the front end of said steam and water space and being disposed substantially adjacent but above the bottom of the shell and being surrounded by the water in said steam and water space, the inlet portion for the rear end of said body opening through another of the sheets of the firebox at a point below the crown sheet.

5. In combination with a locomotive boiler embodying therein a shell and having a firebox at one end thereof and a steam and water space above as well as forwardly of the firebox, said firebox formed to provide a main fire chamber and a combustion chamber having a flue sheet at the front end and having a throat sheet at the junction of said chambers, a water steaming and circulating element in said firebox embodying therein a flat hollow body opening at one end through the crown sheet so as to discharge water and steam into said space, a plurality of inlet portions for said body, one of said inlet portions extending through the combustion chamber and opening through and extending longitudinally of the boiler shell and forwardly of the flue sheet to take in water from the front end of said space, said inlet portion being surrounded by the water in said space and being disposed above the bottom of said shell, the other inlet portion for said body being disposed mainly in the main fire chamber and opening through another sheet of the firebox at a point below the crown sheet.

6. In combination with a locomotive boiler embodying therein a shell having a firebox at its rear end and a steam and water space above as well as forwardly of the firebox and which firebox includes a crown sheet and a flue sheet, a hollow water steaming and circulating element in the firebox and including a body, the top of which presents an elongated opening through

said crown sheet, and a relatively long tubular inlet connected at one end to said body and extending downwardly and forwardly therefrom through the flue sheet into and longitudinally along the bottom portion of the water space but above the bottom of the shell toward the front end of said space so as to be entirely surrounded by the water therein, the other inlet opening through another shell of the firebox other than and at a point below the crown sheet.

7. In combination with a locomotive boiler embodying therein a shell having a water jacketed firebox at its rear end and a steam and water space above as well as forwardly of said firebox and which firebox includes a crown sheet and a flue sheet, a duplex water steaming and circulating means in the firebox, said steaming device comprising two spaced apart front and rear compartments in communication with each other and having a common outlet with inlets at their bottoms, an intake tube communicating with the forward compartment and extending through and forwardly of the flue sheet into and longitudinally of the boiler to a point remote from the flue sheet and in a plane above the bottom of the boiler and entirely surrounded by water in the boiler and a second tube connecting the rear compartment of the steamer with the water space adjacent the firebox.

8. In combination with a locomotive boiler embodying therein a shell having a water jacketed firebox at its rear end and a steam and water space above as well as forwardly of said firebox and which firebox includes a crown sheet and a flue sheet, a water steaming and circulating means of the duplex type in the firebox, said steaming device comprising two spaced apart front and rear compartments in communication with each other and having a common outlet with inlets at their bottoms, an inlet tube communicating with the forward compartment and extending through and forwardly of the flue sheet with the portion projecting through the flue sheet disposed in a substantially horizontal plane and parallel with the boiler flues, the forward end of said tube being remote from the flue sheet and below the cold water inlet of the boiler, means for supporting the forward end of the intake tube within the boiler in spaced relation from the bottom of the boiler whereby the tube is entirely surrounded by water in the boiler and a second tube connecting the rear compartment of the steaming device with the water jacket of the firebox, said second tube entering the water jacket at a lower level than that of the intake tube projecting through the flue sheet.

BERT E. LARSON.
